UNITED STATES PATENT OFFICE.

HENRI VICTOR JULES JOUFFRET, OF PARIS, FRANCE.

INTERNAL-COMBUSTION ENGINE.

1,349,459.

Specification of Letters Patent. Patented Aug. 10, 1920.

Application filed August 25, 1917. Serial No. 188,203.

To all whom it may concern:

Be it known that I, HENRI VICTOR JULES JOUFFRET, engineer, a citizen of the French Republic, residing at Paris, France, have 5 invented certain new and useful Improvements in Internal-Combustion Engines, of which the following is a specification.

This invention relates to internal combustion engines cooled by means of a liquid 10 circulation.

It has for its principal object to enable engines of the class in question to be constructed in a more simple and economical manner than has hitherto been the case.

15 The invention consists essentially in providing engines of the class in question with one or more cylinders, each formed from a tube of circular section, in providing a screw thread at one end of each tube, and a circu-

20 lar step or flange, the position of which is preferably adjustable in the neighborhood of the other end of the tube in providing a head piece or cover so constructed and proportioned that the threaded end of each of

25 the cylinders can be screwed to the same and in providing a jacket so constructed and proportioned that it is adapted to be held in position with one of its extremities resting against the lower edge or face of the 30 head piece or cover and with the other extremity coming against the circular step or flange on each of the cylinders.

The invention further includes certain 35 constructional details which will be more fully described hereafter as well as various methods of carrying the invention into effect and as new industrial products engines of the class in question having the improvements adapted thereto, as well as 40 special parts suitable for the construction of such engines.

In order that the said invention may be clearly understood it will now be described with reference to the accompanying drawings, 45 which, however as will be clearly understood, are given merely by way of example.

Figure 1 of the said drawings shows a transverse section through the axis of one 50 of the cylinders of a four cylinder internal combustion engine constructed according to the invention, the details which are not of

interest in connection with the invention being omitted for the sake of clearness.

Fig. 2 shows partly in longitudinal section and partly in elevation the same engine as shown at Fig. 1.

Figs. 3, 4 and 5, show respectively in transverse section in longitudinal section and in plan, the water jacket of the said 60 engine.

Lastly Fig. 6 shows, to a larger scale, a detail of construction in connection with the second method of carrying out the invention.

65 In constructing a four cylinder internal combustion engine with a water cooling system according to the invention, and as shown in the drawing, the following or some analogous construction is adopted.

70 *a* is a head or cover piece provided with the usual constructional details and comprising valve chambers *a*¹, admission passages *a*² outlet passages *a*³ chambers *a*⁴ for the circulation of water and combustion 75 chambers *a*⁵.

The lower portion of each combustion chamber is bored in such a way that the said portion has an inner diameter slightly greater than the inner diameter of the said 80 chamber, and the wall of the said portion is provided, at the bottom with a screw thread.

The lower face, surface or edge of the head piece or cover is provided with plane 85 portions *a*⁶.

80 The cylinders *b* are made from tubes of circular section, and preferably of steel, having, by preference, an inner diameter similar to that of the combustion chambers *a*⁵ and an outer diameter the same as the lower bored portions of the said chambers. One of the extremities of each of the said cylinders is provided with a screw threaded portion *b*¹ for enabling it to be screwed 90 into the screw thread at the lower part of the chamber *a*⁵ of the head or cover. 95

The cylinders are provided toward their other extremities with circular steps of flanges *b*², coming on the outside. These 100 steps or flanges may be integral with the said cylinders, or by preference they may be constructed, as shown at Fig. 6. In this case *b*² is a ring adapted to screw upon a screw

thread, provided upon a projecting portion b^3 of the cylinder, formed for the purpose. The ring may be kept in place by means of a nut c and a lock nut c^1 . In this way the 5 position of the said ring can be adjusted.

d is a water jacket, preferably made of aluminium and having at the lower portion a sort of base plate d^1 provided with circular holes of a diameter about equal to the 10 outer diameter of the cylinders b and of such size that when the cylinders are passed through the said circular holes, sufficient space is left between the walls of the jacket and the cylinders for the circulation of the 15 cooling liquid. The jacket is slightly shorter than the distance between the screw threaded ends of the cylinders and their circular flanges and it has at its upper extremity a plane face d^2 adapted to come 20 into contact with the plane surface a^6 on the head piece or cover.

With this construction in order to assemble the engine it is sufficient to engage the cylinders in the holes at the base of the water jacket, and to bring them into such a position that the steps or flanges b^2 come against the lower face of the said base, then to screw the cylinders into the head piece in such a way that the upper plane surface d^2 of the water jacket comes against the plane surface a^6 of the head piece.

It will of course be understood that in cases where the step b^2 is removable, the cylinders may be screwed in the first instance into position in the head piece or cover; the water jacket being afterward placed in position and then the rings b^2 can be screwed on to the cylinders.

In some cases it may be desirable, in addition to providing the construction just described, to provide chambers a^4 , as shown in the drawing, for the water circulation, and adapted to communicate with the space between the cylinders and the water jacket.

It is to be observed that the invention is not limited in any way to the particular methods of carrying the same into effect just described but that modification may be made without departing from the principle 50 of the said invention as defined by a fair interpretation of the claims.

What I claim and desire to secure by

Letters Patent of the United States of America is:—

1. In an internal combustion engine, the 55 combination of a head piece comprising a combustion chamber and the usual associated parts, for each cylinder, a screw threaded portion at the lower part of the said head piece for each combustion chamber, a cylinder provided with a screw thread and adapted to be screwed to each such screw threaded portion, a projecting portion of the head piece extending beyond each cylinder when in position, a jacket adapted to surround each cylinder with a certain amount of clearance, and having a part at one end adapted to contact with the projecting portion of the head piece, a ring adapted to surround each cylinder and means for securing 70 the said ring to the cylinder so that the lower end of the jacket is held in close contact therewith when the cylinder is in position, all substantially as described.

2. In an internal combustion engine the 75 combination of a head piece comprising a plurality of combustion chambers and the usual associated parts, a screw threaded portion at the lower part of each combustion chamber, an appropriate number of cylinders each provided at one end with a screw thread adapted to screw to one of the combustion chambers, projecting portions of the head piece extending beyond the sides 80 of the cylinders, a jacket provided with a base plate having an appropriate number of holes and adapted to be passed over the cylinders, the said jacket being furnished 85 with walls adapted to surround the cylinders with a certain amount of clearance and to come at one end into close contact with the aforesaid projecting portion of the head piece and steps connected with each of the cylinders adapted to come into contact with and grip the other end of the jacket when 90 the cylinders are in position all substantially as described.

In testimony whereof I have hereunto set my hand in presence of two subscribing witnesses.

HENRI VICTOR JULES JOUFFRET.
